UNITED STATES PATENT OFFICE.

WILLIAM T. URIE, OF KANSAS CITY, MISSOURI.

MINING-DREDGE.

SPECIFICATION forming part of Letters Patent No. 678,147, dated July 9, 1901.

Application filed July 13, 1900. Serial No. 23,524. (No model.)

To all whom it may concern:

Be it known that I, WILLIAM T. URIE, a citizen of the United States of America, residing at Kansas City, in the county of Jackson and 5 State of Missouri, have invented certain new and useful Improvements in Mining-Dredges; and I do hereby declare that the following is a full, clear, and exact description of the invention, such as will enable others to make 10 and use the same, reference being had to the accompanying drawings, forming a part of this specification.

The objects of my invention are, first, mechanism upon a mining-dredge controlling the 15 reciprocal movements of the dredge in passing over the material to be removed; second, the regulation of the degrees of speed of the controlling mechanism, and, third, the impulse to the dredge-boat while excavating the 20 material.

The invention consists in the novel construction and combination of parts, such as will be first fully described, and specifically pointed out in the claims.

25 In the drawings, Figure 1 is a side elevation of the mining-dredge with the excavating devices in position for removing the material and the dredge moored in the stream, showing the invention applied thereto. Fig. 30 2 is a plan view of the improved dredge, showing the alternately wound and unwound boat-moving cables and the position of the dredge-boat in dotted lines at the completion of the lateral movements. Fig. 3 is a view of the 35 dredge, taken at the forward end, with portions of the side floats and operating-levers to the friction-gear broken away. Fig. 4 is a plan view in detail of the mechanism for moving the pinion of the friction-gear upon the power-

40 conveying shaft into engagement with the disk. Fig. 5 is an enlarged end view in detail of the friction-gear, showing the pinion and its adjusting-rod. Fig. 6 is a vertical sectional view of the pinion, showing the external grooved collar and the ring, and also

45 showing the groove in the pinion for the spline on the power-shaft. Fig. 7 is a horizontal sectional view of the eccentric journal for the shaft carrying the pinion of the friction-gear, taken upon the line $x-x$ of Fig. 8.

50 Fig. 8 is a vertical sectional view taken upon the line $y-y$ of Fig. 7. Fig. 9 is a vertical

sectional view of the devices for adjusting the position of the rod carrying the pinion of the friction-gear.

55

Similar letters of reference indicate corresponding parts in all the figures.

Referring to the drawings, A represents a dredge boat or barge of the proper dimensions for carrying the dredging appliances 60 and which is provided with a horizontal deck a , extending the length and width of the boat.

In the forward end of the dredge-boat A is a well a^2 , extending through said end and rearwardly a considerable distance for the 65 convenient operation of the dredging devices, the sides $a^3 a^3$ of the well being hermetically closed against the entry of water into the boat. Upon the deck a , upon each side of and toward the rear end of the well a^2 , are the 70 upright frames B B, each composed of the standards $b b$, arranged a considerable distance apart from each other and extending upwardly the proper height above the deck a . The upper ends of the standards $b b$ in each 75 frame B are connected by a horizontal beam b^2 , extending in the longitudinal direction of the boat, and said frames B B are connected at their forward ends by the transverse beam b^3 and the rear ends by the transverse beam b^4 . Connected with each standard $b b$ in each frame B, a short distance downwardly from the beam b^2 , is a horizontal beam b^5 , which supports the shaft for the large sprocket-wheel actuating the material-conveying buckets. 85 With the standards $b b$ in said frame B, at a point about one-third the distance upwardly from the deck a toward the beam b^2 , is connected a horizontal beam b^6 , which beam supports the shaft carrying the disk, hereinafter 90 described.

Upon one side of the frame B, near the forward end and in the same plane as the beam b^2 , is a platform B', consisting of the beam b^7 , which is connected at one end with an outward extension of the transverse beam b^3 at the forward end of the frame B, and the short beam b^8 , connected with the other end of beam b^7 and extending at right angles thereto and connected with the beam b^2 .

95 100 A little over one-half the distance from the platform B' to the deck a and directly beneath the said platform is a horizontal frame C, composed of the longitudinal beam c and the

short beams $c' c^2$, extending at right angles thereto, and the inner ends of the beam secured to the standard b , and the inner end of the beam c^2 to a short standard b^9 , arranged 5 at a point on the deck a equidistant from the standards $b b$ and secured to the horizontal beam b^6 . About equidistant from the frame C to the deck a and directly beneath said frame C is a frame D, which is of the same 10 dimensions and secured to the outer side of frame B in like manner as frame C.

E represents the main power-shaft, conveying power to the dredging devices, which is journaled upon the beams $b^5 b^5$ in the frames 15 B B at a point about one-third the distance rearwardly from the forward standards $b b$, and with which shaft is pivotally connected at one end the longitudinal trussed beams F F of the ordinary construction. Upon shaft E, 20 on the inner side of the beams F F, are the sprocket-wheels $e e$. In the lower end of the truss-beams F F, upon the transverse shaft e^2 , are the sprocket-wheels $e^3 e^3$. Over the sprocket-wheels $e e$, at the upper end of the 25 beams F F, is extended one end of the sprocket-chains $e^4 e^4$, the other ends of which chains are extended over the sprocket-wheels $e^3 e^3$ and the ends of the sprocket-chains connected together in the usual manner. Upon the upper 30 edges of the beams F F are journaled the series of shafts $f f$, which are arranged a short distance apart and upon each one of which shafts are friction-rollers $f' f'$, which sustain the weight of the sprocket-chains $e^4 e^4$. Upon 35 the sprocket-chains $e^4 e^4$ are secured in the usual manner the series of material-excavating buckets G, which are arranged the proper distance apart and are of the usual description of excavator-bucket.

40 For the purpose of raising the lower end of the truss-beams and also regulating the depth of entry of the excavator-buckets within the material upon the deck a and at the forward end of the boat upon each side 45 of the well a^3 are the standards $h h$, the upper ends of which standards are inclined forward at an angle of inclination to the deck a and the upper end connected together by a transverse beam h' . The standards $h h$ are 50 supported in their outward inclined position by a frame H on each side of the well a^3 , each frame having the horizontal beam h^2 , connected with the forward beam b of each frame B at one end and with the standards $h h$ at the other end. These beams h^2 are 55 suitably trussed at $h^3 h^3$ upon the upper side and also by the beams $h^4 h^4$ upon the lower side, the latter beams being connected with the deck a . Upon the transverse beam h' is 60 a block h^5 , and connected with the lower ends of the truss-beams F F is a sheave or block h^6 , with which sheave is connected one end of an elevator chain or rope h^7 , the other end of which rope is passed through the 65 sheave h^6 , thence through the sheave h^5 , and thence to a convenient point upon the frame B for the convenience of operation.

Upon each end of the rotating shaft E on the frames B B, which extend a short distance beyond the outer sides of the said frame, are the sprocket-wheels I I, which are of considerable size. Upon the transverse beams $b^6 b^6$, about one-third the distance from the forward standards $b b$ on the frames B B toward the rear standards in said frames, is 70 journaled the transverse shaft K, the ends of which shaft extend a short distance beyond the outer side of said frames, and upon said ends are the small sprocket-wheels $k k$. Over the sprocket-wheels I I are extended 80 one end of the sprocket-chains $k' k'$, the other ends of which chains extend over the sprocket-wheels $k k$ and the ends of said chains connected together in the usual manner. 85

Upon the under side of the beam b^6 in the frame B, having platforms C D a short distance rearwardly from a vertical line extending through the shaft K, is journaled one end of a transverse power-shaft L, the other end 90 of which shaft extends to the frame B upon the other side of the well a^3 and a short distance beyond the outer side of said frame and is journaled in the upper end of a support or standard M upon the deck a . Upon 95 the shaft K, on the inner side of frame B, is a large gear k^2 , and upon the shaft L is a small gear l , which meshes with the gear k^2 on K. Upon shaft L, on the inner side of the standard M, is a band-wheel N. 100

Upon the outer end of shaft K, extending beyond the outer side of the frame B, having the frames C D, is a large disk O. Upon the inner side of the longitudinal beam c of the frame C, about midway from the beams $c c^2$, is an eccentric journal-box P, consisting of a wall-plate p , (see Figs. 7 and 8,) upon which is a casing p' , having the vertical opening $p^2 p^2$, in which opening is a rotating cylindrical casting p^3 , upon the lower end of which is an annular flange p^4 , which retains the casting or journal within the opening p^2 . Upon the upper end of the casting p^3 , which extends below the under side of the casing p' , is a horizontally-extended arm or lever p^5 . Through the cylindrical casting p^3 , in a vertical direction and at one side of the line of the axis of said casting, is a shaft-opening p^6 . Upon the inner side of the longitudinal beam in the frame D is an eccentric journal-box, 115 which is the same as the box P and inverted in position. 120

In the journal-boxes P P is a rotating shaft R, the upper end of which shaft extends upwardly to the height of the journal-box P 125 on the beam C. Upon the platform B' is a post S, through which extends in a vertical direction an opening s' . Upon the top of the post S is a nut s^2 , upon the lower edge of which nut is an annular flange s^3 . 130

s^4 is an operating-wheel, of which the nut s^2 forms the hub, the radial spokes s^5 extending from the nut s^2 to the rim of the wheel. s^6 is an annular collar secured to the top

of the post S by the bolts s^7 and having an internal annular flange s^8 , which extends over the annular flange s^3 on the nut s^2 .

Upon the shaft R opposite the disk O is 5 a small friction wheel or pinion T, upon the under side of which wheel is an annular collar t, in which collar is a groove t', extending around said collar, and in which groove is a ring t''. Upon the shaft R is a feather or 10 spline r, extending nearly the distance from one journal-box P to the other. In the friction-wheel T and collar t is a groove t'', which receives the spline r, so as to move upward and at the same time rotate with said shaft R.

15 U is an adjusting-rod for the pinion or wheel T, the upper end of which rod is screw-threaded and extends upwardly through the platform B' and the post S and the nuts s^2 on said post. The lower end of the rod U is bent 20 at right angles at u' and said bent end perforated and extended over the pin t' on the ring t''. In an opening in pin t' is a split key t'', which secures the bent end of the rod U to the ring t''. Upon the outer side of the beam 25 c of the frame C and upon the corresponding beam in the frame D and the beam b' are journal-boxes v v, in which boxes is a vertical shaft V. Upon the shaft V above and below the plane of the platforms C D are 30 crank-arms v' v'', and with said arms are pivotally connected one end of a crank-rod v'', the other ends of which rod are pivotally connected with the arms p' in the eccentric journals P P. Upon the upper end of the rod V, 35 which extends above the platform B', is a crank v''. The lower end of shaft R extends downwardly nearly to the deck a, and upon said end is a bevel-gear r'.

Upon the deck a on the outer side of the 40 frames H H are rope-winding drums W W, mounted upon a longitudinal rotating shaft w, journaled in the uprights w' w''. With said drums W W are connected and also wound the inner ends of said cables w' w'', 45 the outer ends of said cables having loops w'', which extend over fixed supports w' w' in the bed of the stream or upon the banks of the stream, as preferred. The inner end of one shaft w extends in the direction of the bevel-gear r' in the shaft R, and upon said end is a 50 bevel-gear w'', which meshes with the said gear r''. On the shafts w w are sprocket-wheels w' w''. Over the ends of the sprocket-wheels w' w'' is extended one end of a sprocket-chain w' and the two ends of the chain secured together in the usual manner. Upon the deck a at the rear end of the boat is a 55 boiler X and an engine Y, receiving steam from the boiler through pipe y. Upon the 60 driving-shaft of the engine is a band-wheel y', over which extends one end of a belt or band y'', the other end of which belt is extended over the band-wheel N on the shaft L in the frames B B and the two ends connected together in the usual manner.

Z Z are vertically-movable spuds or spars at the rear end of the dredge-boat, which are

of considerable length, so as to extend in the bed of the stream and act alternately in change of the angle of the boat. These spuds 70 are square in cross-section and are slidable in the square boxes z z, secured to the rear end of the dredge-boat. These spuds are employed alternately and are raised and lowered in position by an ordinary rope or chain z', 75 connected at one end with the spud near its lower end, the upper end extending upwardly between the spud and the end of the boat in the grooves z' in the boxes Z Z, thence over the pulleys z' z' in the standards z' z' on the 80 deck a, and thence to and connected with the ordinary winches z' z' on the deck a.

The dredge-boat being moored in position in the stream, as shown in Figs. 1 and 2, by the cables w' w' and one of the spuds Z, which 85 acts as a pivot, and the truss-frames F F, carrying the excavator-buckets G G, lowered in position at their outer ends by the releasing of the elevator-rope h' in the sheave h' h'', so as to reach the material in the bed of the 90 stream, the operation is as follows: Power from the engine Y is transmitted through the belt y' to the shaft L through the band-pulley N, thence from the shaft L to the shaft K, upon which is the disk O, through the 95 meshing gear l and k', and from the shaft K to the shaft E through the sprocket-wheels k and I and the sprocket-chain k', which power actuates the sprocket-wheels e and e' on the truss-frames F F and the chain e'', and the 100 series of excavator-buckets G are caused to move toward and enter the material in the bed of the river, and the material is excavated by the buckets G, is dumped upon an inclined chute G', and thence upon the deck 105 a, and from which it is removed by any well-known means.

In the excavation of auriferous material the usual screens are employed to screen the material and the debris dumped into the stream. During the operation of the 110 buckets G G the rod V is operated by the crank v'' by the person stationed upon the platform B' to throw the arms v' from the position seen in dotted lines in Fig. 4 to the position shown in full lines, which movement 115 actuates the crank-rods v' v'' and the arms p' p'' on the eccentric journal-boxes P P, and the shaft R is moved a slight degree inwardly toward the disk O, which action causes the pinion T to come into close contact with the face of the 120 disk O, and power is transmitted from said disk to the shaft R, thence through the bevel-gear r' and w'' to the horizontal shafts w w, carrying the drums W W, which shafts w w are in power connection with each other 125 through the sprocket-wheels w' w'' and the chain w'. Thus the movement of the drums W W are in the same direction, and the cables w' w'', connected with the separate fixed points w' w'', are alternately wound and unwound upon the drums, and the forward end of the dredge-boat is moved in one direction toward one fixed point w', laterally from the 130 position shown in full lines to the position

shown in dotted lines, Fig. 2, the course of movement being from the spud Z near the far side of the boat. The position of the pinion T at the time of its contact with the disk O being at or near the periphery of the disk, as seen in full lines in Fig. 5, as soon as the lateral movement of the dredge-boat before mentioned is completed the operator upon the platform B operates the shaft V to move the pinion T away from contact with the disk O. The spud Z, which has acted as a pivot to the movement, is raised in position and the other spud lowered in position. The operator then rotates the wheel s^4 upon the post S in the proper direction, and the shaft U is moved upwardly within the nut s^2 , carrying the pinion T across the face of the disk O to the position seen in dotted lines in Fig. 5. The shaft V is then operated to move the pinion T into engagement with the disk O, the movement of the pinion acting to reverse the movement of shaft R, and consequently the direction of the movement of the drums W W, and the forward end of the dredge-boat moves in an opposite lateral direction to the first movement described, these lateral movements being reciprocal as often as the position of the pinion T is changed relatively to the disk O, and at the same time the spuds Z Z take position one in advance of the position of the other, imparting an impulse forward to the dredge-boat, so that as the movement of the boat progresses other fixed points are found with which to connect the cables $w^2 w^3$, and in this manner the excavation is obtained over a large area of the material. In order to impart a slow degree of speed to the drums W W, the pinion T is moved toward the center of the disk O, these adjustments of position being obtained in the manner heretofore described, the effect being that while the excavator-buckets are performing their work at an accelerated or slow degree of speed, as may be desired, the degree of speed of movement laterally of the dredge is regulated to accommodate any condition of the material and also at a slow degree of speed to meet an accelerated degree of speed of the buckets.

It is obvious that in place of the separate drums W W one drum may be employed when found advantageous, over which the intermediate portion of a single cable may be wound, the ends of the cable being connected

with fixed points $w^4 w^4$. The friction-gear, 55 whenever sudden strain is sustained by the cables $w^2 w^2$, will afford the relief necessary in such instances. The frames B B may be at the extreme forward end of the boat, if preferred. 60

Having fully described my invention, what I now claim as new, and desire to secure by Letters Patent, is—

1. A dredge-boat, and alternating cable winding and unwinding drums thereon, and 65 separate cables having their free ends extending in opposite directions and laterally from the forward end of said dredge-boat, and connected with suitable, fixed points, separate vertically-movable boat-anchoring spuds 70 or spars connected with the rear end of said dredge-boat and adapted to be lowered in position alternately, a main power-shaft, and an engine and its driving-shaft, power-conveying devices connected with the driving-shaft 75 of said engine and the main power-shaft, a separate, horizontal shaft upon said boat, actuated by the main power-shaft and a vertical power-transmitting shaft connected with and actuating the drums carrying said cables, 80 and suitable friction-gearing connecting said horizontal and said vertical power-transmitting shafts.

2. A dredge-boat and alternating cable winding and unwinding drums thereon, and 85 separate power-shafts carrying said drums, and sprocket-wheels on said shafts, and a sprocket-chain extending over said sprocket-wheels, cables upon said drums, having their free ends extending laterally from the forward end of said boat and connected with separate fixed points, a main power-shaft journaled upon said boat, a horizontal shaft upon said boat and an engine and its driving-shaft, and power-conveying devices connect- 90 ed with the driving-shaft of said engine and said horizontal shaft, and also with said horizontal shaft and said main power-shaft, a vertical power-shaft connected with one of the drum-carrying shafts and friction-gear connect- 95 ing the said horizontal and vertical power-transmitting shafts, and means substantially as described for changing the speed 100 of said gear.

WILLIAM T. URIE.
